CAR TRUCK BOLSTER

Karl R. Hammerstrom, Dormont, Pa., assignor to
 The Railroad Research Bureau of The Manufacturing Companies of The United States Steel Corporation

Application October 14, 1935, Serial No. 44,976

9 Claims. (Cl. 105—226)

This invention relates to car truck bolsters. One of the objects is to produce a practical bolster made mainly of rolled steel parts. Another object is to produce a light weight bolster that is sufficiently rugged to meet the severe operating conditions encountered in such constructions. Other objects may be inferred from the following disclosure.

A specific example of a car truck bolster that embodies the principles of the present invention is illustrated by the accompanying drawings, in which:

Figure 1 shows the top of this bolster.

Figure 2 shows the side.

15 Figure 3 is a longitudinal section taken in a vertical plane from the line III—III in Figure 1.

Figures 4, 5 and 6 are cross-sections respectively taken from the lines IV—IV, V—V and VI—VI in Figure 2.

20 Figure 7 shows an end.

Figures 8 and 9 show cross-sections of rolled steel plate sections from which various parts of the bolster are worked.

Figure 10 shows the top of a modification of the 25 bolster.

Figure 11 shows the side of this modification.

Figure 12 is a longitudinal section taken in a vertical plane from the line XII—XII in Figure 10.

Figures 13, 14 and 15 are cross-sections respectively taken from the lines XIII—XIII, XIV—XIV and XV—XV in Figure 11.

The bolster illustrated by Figures 1 through 7 includes inverted and upright channel sections 1 and 2 having the edge portions of their respective flanges arranged together in abutting relationship and interfastened by welding. The inverted channel section 1 has a widened central portion 1^a, and the upright channel section 2 progressively deepens from its ends to its center 40 and has its flanges shaped, as at 2^a, to accommodate the widened central portion 1^a of the inverted channel section 1.

A center plate 3 is welded to the top of the widened central portion 1^a of the inverted channel 45 section 1, and a pair of plates 4 are welded in vertical planes transversely to the inside of the inverted channel section 1 beneath this center plate 3 in equally spaced relationship respecting the transverse center line of this inverted channel 50 section. The flanges of the upright channel section 2 have vertical slots 2^b formed in them in line with the plates 4, the latter having lengthened lower portions 4^a that project through these slots and which are welded to the outsides of these 55 flanges.

A third channel section 5 is welded parallel to the inverted channel section 1 in an upright position beneath the center plate 3 between the plates 4, its flanges being welded to the inside of the web of the inverted channel section 1 and of this third channel section 5 are apertured, as at 1^b and 5^a, to accommodate the king-pin that is passed through the center plate 3 when the bolster is in service. The center plate 3 has a bore 3^a and a 10 depending boss 3^b that fits in the aperture 1^b so as to facilitate assembly and help maintain the center plate in position in service.

This center plate is, of course, provided with a bore 3^a for the purpose of receiving such a king-pin, the aperture 1^b in the inverted channel section 1 being sufficiently large to accommodate the boss 3^b surrounding this bore 3^a, but still functioning to accommodate the passage of the king-pin. A king-pin support 6 is welded beneath the aperture 5^a in the web of the third channel section 5 for the purpose of preventing the king-pin from dropping completely to the inside of the web of the upright channel section 2. This bracket is illustrated as being in the form of an upright channel section with the ends of its flanges welded to the web of the third channel section 5 to either side of the aperture 5^a. Other forms of supports may be substituted.

A second pair of plates 7 are welded in vertical planes transversely to the inside of the inverted channel section 1 in equally spaced relationship respecting the first named pair of plates 4, and a third pair of plates 8 are welded in vertical planes between the first named pair of plates 4 and this second pair of plates 7 in line with the longitudinal center line of the inverted channel section 1.

The strength of the bolster at its central portion is still further increased by a fourth pair of plates 9 that are welded transversely to the inside of the upright channel section 2 in line with the first named pair of plates 4, the opposing side edges of these two pairs of plates being arranged as closely as is possible.

At each end of the bolster a pair of column 45 guides 10 are welded to the flanges of both of the channel sections 1 and 2, and a fifth pair of plates 11 are welded in vertical planes transversely to the insides of both these channel sections between each of these pairs of column 50 guides 10 in equally spaced relationship respecting the vertical center lines of the latter. The inside ones of these plates 11 are strengthened by triangular plates 12 that are welded between them and the inside of the web of the upright 55

channel section 2 in line with the longitudinal center line of the latter. The outside ones of the plates 11 are strengthened by plates 13 that are welded between the latter and the inner sides of the webs of both the channel sections 1 and 2. Preferably, in each instance there are two of these plates 13 and they are welded parallel to the longitudinal center line of the two sections 1 and 2 in equally spaced relationship respecting this line.

10 The flanges of the inverted channel section 1 are further strengthened at positions between the ends and center of this section by means of a plurality of plates 14 that are welded transversely to the inside of this section.

15 Various hand-holds 15 are formed at appropriate positions. Since there is danger of condensed moisture accumulating within the upright channel section 2, the web of this section 20 is provided with properly positioned drain holes 16.

25 The two channel sections 1 and 2 are particularly characterized in that they are respectively worked to form from rolled steel plate sections, illustrated by Figures 8 and 9, which in each instance provide longitudinally extending central portions 17 of greater thicknesses than their edge portions 18, so that at least the major portions of the webs of these channel sections include 30 the central portions 17 of these plate sections and at least the major portions of the flanges of these channel sections include the edge portions 18 of these plate sections.

35 The chief difference between these plate sections as they are illustrated by the drawings is the greater extents of the edge portions of the plate section that is used to form the upright channel section 2, this being necessary because of the center deepening of the latter.

40 The modification of the bolster illustrated by Figures 10 through 15 is generally similar to the bolster which has been described, and for this reason similar numerals are used wherever possible.

45 It will be noted that the aperture 5^a in the inverted channel section 5 is bounded by a depending flange 5^b formed by displacement of the web of this channel section 5. This provides a larger bearing surface on which the king-pin 50 may bear.

55 Furthermore, longer plates 7^a and 8^a are substituted for the plates 7 and 8 shown in the case of the first described construction, and the flanges of the upright channel section 2 are recessed to form slots 19 beneath the plates 4^a and at right angles to the same, other plates 20 being welded in horizontal planes to the bottoms of the plates 7^a and extending through the slots 19 to the 60 outsides of the flanges of the two channel sections where they are welded to the same.

65 Likewise, a longer plate 14^a is substituted for the plates 14, the flanges of the inverted channel sections 1 are recessed as at 21 and plates 22 are welded in horizontal planes to the bottoms of the plates 14^a, passed through the slots 21 and welded to the outside of the flanges of the two channel sections.

70 Instead of the plates 11 being used between the column guides 10, special channel sections 23 are substituted. This section 23 in each instance has a deepened central portion 23^a and web projections 23^b, and is welded transversely between the insides of the two channel sections 1 and 2 in an inverted position between each of the pairs of 75 column guides 10, the latter and the flanges of at

least one of the channel sections 1 and 2 having slots 24 formed in them in line with the projections 23^b. These projections extend through these slots and are welded to the flanges of said channel sections. The inside ones of the flanges of the 5 special channel sections 23 are strengthened by the same triangular plates 12 described previously, while the outside ones of their flanges are strengthened by plates 25 which are associated with the bolster and these flanges in the same 10 manner as are the plates 13 previously described, and which differ only slightly in shape. Practically the only other difference between the two constructions consists in the sharp downward angling, as at 1^c, of the ends of the webs of the 15 inverted channel section 1, this bringing the web against the outsides of the webs of the special channel sections 23 at the ends of the bolster and permitting them to be welded together through the hand-holds at these positions. 20

I claim:

1. A car truck bolster including inverted and upright channel sections having the edge portions of their respective flanges arranged together and interfastened by welding, said inverted channel section having a widened central portion and said upright channel section progressively deepening from its ends to its center and having its flanges shaped to accommodate said widened central section of said inverted channel section, a center plate welded to the top of said widened central portion of said inverted channel section, stiffening members welded transversely to the inside of said inverted channel section beneath and adjacent said center plate, column guides welded to the outsides of the flanges of said channel sections at positions at least adjacent the latter's ends, stiffening members welded transversely to the insides of said channel sections between said column guides and stiffening 30 members welded transversely to the inside of at least one of said channel sections at positions between the center and ends of the same, each of said channel sections being worked to form from rolled steel plate sections providing longitudinally 35 extending central portions of greater thicknesses than their edge portions, so that at least the major portions of the webs of said channel sections include said central portions of said plate sections and at least the major portions of the 40 flanges of said channel sections include said edge portions of said plate sections.

2. A car truck bolster including inverted and upright channel sections having the edge portions of their respective flanges arranged together and interfastened by welding, said inverted channel section having a widened central portion and said upright channel section progressively deepening from its ends to its center and having its flanges shaped to accommodate said widened 55 central section of said inverted channel section, a center plate welded to the top of said widened central portion of said inverted channel section, a pair of plates welded in vertical planes transversely to the inside of said inverted channel section beneath said center plate in equally spaced 60 relationship respecting the transverse center line of said inverted channel section, the flanges of said upright channel section having vertical slots formed therein in line with said plates and the latter having lengthened lower portions that project through said slots and which are welded to the outsides of the flanges of said upright channel section, a third channel section that is parallel 65 to said inverted channel section in an upright 70 position and having its flanges welded to the flanges of the third channel section, the flanges of the third channel section being worked to form from rolled steel plate sections 75 providing longitudinally extending central portions of greater thicknesses than their edge portions, so that at least the major portions of the webs of the third channel section include said central portions of the plates of the third channel section and at least the major portions of the flanges of the third channel section include said edge portions of the plates of the third channel section.

position beneath said center plate between said pair of plates with its flanges welded to the inside of the web of said inverted channel section, the webs of said inverted channel section and of said 5 third channel section being apertured to accommodate a king-pin when the latter is passed through said center plate, means for preventing said king-pin from dropping completely to the inside of the web of said upright channel section, 10 a second pair of plates welded in vertical planes transversely to the inside of said inverted channel section in equally spaced relationship respecting the first named pair of plates, and a third pair of plates welded in vertical planes between the 15 first named pair of plates and said second pair of plates in line with the longitudinal center line of said inverted channel section.

3. A car truck bolster including inverted and upright channel sections having the edge portions of their respective flanges arranged together and interfastened by welding, said inverted channel section having a widened central portion and said upright channel section progressively deepening from its ends to its center and having its 25 flanges shaped to accommodate said widened central section of said inverted channel section, a center plate welded to the top of said widened central portion of said inverted channel section, a pair of plates welded in vertical planes trans- 30 versely to the inside of said inverted channel section beneath said center plate in equally spaced relationship respecting the transverse center line of said inverted channel section, the flanges of said upright channel section having vertical slots 35 formed therein in line with said plates and the latter having lengthened lower portions that project through said slots and which are welded to the outsides of the flanges of said upright channel section, a third channel section that is parallel 40 to said inverted channel section in an upright position beneath said center plate between said pair of plates with its flanges welded to the inside of the web of said inverted channel section, the webs of said inverted channel section and of said 45 third channel section being apertured to accommodate a king-pin when the latter is passed through said center plate, means for preventing said king-pin from dropping completely to the inside of the web of said upright channel section, 50 a second pair of plates welded in vertical planes transversely to the inside of said inverted channel section in equally spaced relationship respecting the first named pair of plates, and a third pair of plates welded in vertical planes between the first 55 named pair of plates and said second pair of plates in line with the longitudinal center line of said inverted channel section, each of said channel sections being worked to form from rolled steel plate sections providing longitudinally ex- 60 tending central portions of greater thicknesses than their edge portions, so that at least the major portions of the webs of said channel sections include said central portions of said plate sections and at least the major portions of the 65 flanges of said channel sections include said edge portions of said plate sections.

4. A car truck bolster including inverted and upright channel sections having the edge portions of their respective flanges arranged together and interfastened by welding, a pair of column guides welded to the flanges of both said channel sections at least adjacent each of the latters' ends, a pair of plates welded in vertical planes transversely to the insides of said channel sec- 70 tions between each of said pairs of column guides

and in equally spaced relationship respecting the vertical center lines of the latter and a plurality of plates welded in vertical planes to said pairs of plates and said channel sections parallel to the latters' longitudinal center lines, each of said channel sections being worked to form from rolled steel plate sections providing longitudinally extending central portions of greater thicknesses than their edge portions, so that at least the major portions of the webs of said channel sec- 10 tions include said central portions of said plate sections and at least the major portions of the flanges of said channel sections include said edge portions of said plate sections. 5

5. A car truck bolster including inverted and 15 upright channel sections having the edge portions of their respective flanges arranged together and interfastened by welding, a pair of column guides welded to the flanges of both said channel sections at least adjacent each of the 20 latters' ends, a special channel section that has a deepened central portion and web projections and which is welded transversely between the insides of said channel sections in an inverted position between each of said pairs of column 25 guides, the latter and the flanges of at least one of said channel sections having slots formed therein in line with said projections and the latter extending through said slots and being welded to the flanges of said channel sections, 30 and a plurality of plates welded to the outside of the flanges of said special channel sections and to the insides of said inverted and upright channel sections in vertical planes. 35

6. A car truck bolster including inverted and 40 upright channel sections having the edge portions of their respective flanges arranged together and interfastened by welding, a pair of column guides welded to the flanges of both said channel sections at least adjacent each of the 45 latters' ends, a special channel section that has a deepened central portion and web projections and which is welded transversely between the insides of said channel sections in an inverted position between each of said pairs of column 50 guides, the latter and the flanges of at least one of said channel sections having slots formed therein in line with said projections and the latter extending through said slots and being welded to the flanges of said channel sections, 55 and a plurality of plates welded to the outsides of the flanges of said special channel sections and to the insides of said inverted and upright channel sections in vertical planes, each of said channel sections being worked to form from rolled steel plate sections providing longitudinally extending central portions of greater thicknesses than their edge portions, so that at least the major portions of the webs of said channel sections include said central portions of said plate 60 sections and at least the major portions of the flanges of said channel sections include said edge portions of said plate sections. 65

7. A car truck bolster including inverted and 70 upright channel sections having the edge portions of their respective flanges arranged together and interfastened by welding, a center plate fastened to the top of the web of said inverted channel section at the latter's center, stiffening members welded transversely to the inside of 75 said inverted channel section beneath said center plate, column guides fastened to the outsides of the flanges of said channel sections at positions at least adjacent the latters' ends, stiffening members welded transversely to the insides of 75

said channel sections between said column guides, plates welded in vertical planes transversely to the inside of said inverted channel section at positions between the center and ends of the 5 flanges of one of the same, said channel sections being recessed to form a slot beneath said plates and at right angles thereto, and other plates welded in horizontal planes to the bottoms of the first named plates, said other plates extending 10 transversely of said channel sections through said slots and being welded to the outsides of the flanges of said channel sections.

8. A car truck bolster including inverted and upright channel sections having the edge portions 15 of their respective flanges arranged together and interfastened by welding, a center plate fastened to the top of the web of said inverted channel section at the latter's center, stiffening members welded transversely to the 20 inside of said inverted channel section beneath said center plate, stiffening members welded transversely to the inside of each upright channel section in line with the first named members, the

bottoms of said first named members and the tops of the second named members being in contact, column guides fastened to the outsides of the flanges of said channel sections at positions at least adjacent the latters' ends, stiffening members welded transversely to the insides of said channel sections between said column guides and stiffening members welded transversely to the inside of at least one of said channel sections at positions between the center and ends 10 of the same. 5

9. A car truck bolster including inverted and upright channel sections having the edge portions of their respective flanges arranged together and interfastened by welding, said inverted channel section having a widened central portion and said upright channel section progressively deepening from its ends to its center and having its flanges shaped to accommodate said widened central section of said inverted 20 channel section. 15
